US0D1016021S

(12) **United States Design Patent** (10) **Patent No.:** **US D1,016,021 S**
(45) **Date of Patent:** **** Feb. 27, 2024**

(54) **CONNECTOR HOUSING**

(71) Applicant: **Japan Aviation Electronics Industry, Limited**, Tokyo (JP)

(72) Inventor: **Yusuke Obata**, Tokyo (JP)

(73) Assignee: **JAPAN AVIATION ELECTRONICS INDUSTRY, LIMITED**, Tokyo (JP)

(**) Term: **15 Years**

(21) Appl. No.: **29/818,401**

(22) Filed: **Dec. 8, 2021**

(30) **Foreign Application Priority Data**

Jun. 23, 2021 (JP) ..... 2021-013640 D

(51) **LOC (14) Cl.** **13-03**

(52) **U.S. Cl.**

USPC **D13/147**

(58) **Field of Classification Search**

USPC D13/107, 123, 133, 146, 147, 154, 173, D13/183, 199, 184

(57) **CLAIM**

The ornamental design for a connector housing, as shown and described.

DESCRIPTION

FIG. 1 is a front elevational view of a connector housing showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view showing a front, top and right side thereof;

FIG. 8 is a perspective view showing a rear, bottom and left side thereof;

FIG. 9 is a perspective view showing a front, right and bottom side thereof; and,

FIG. 10 is a perspective view showing a rear, left and top side thereof.

The broken line showing of the connector housing is for the purpose of illustrating portions of the article and forms no part of the claimed design.

1 Claim, 10 Drawing Sheets
